HAT

Max Gross, Buffalo, N. Y., assignor to Chic Maid
Hat Company, Inc., Buffalo, N. Y., a corporation of New York

Application April 1, 1953, Serial No. 24,296

Term of patent 3½ years

(Cl. D3—13)

To all whom it may concern:

Be it known that I, Max Gross, a citizen of the United States of America and residing at Buffalo, in the county of Erie and State of New York, have invented a new, original, and ornamental Design for a Hat, of which the following is a specification, reference being had to the accompanying drawing, forming part thereof.

Fig. 1 is a side perspective view of a hat embodying my new design.

Fig. 2 is a side elevational view thereof, the opposite side elevational view being substantially the same.

Fig. 3 is a front elevational view thereof.

Fig. 4 is a rear elevational view thereof.

I claim:

The ornamental design for a hat, substantially as shown and described.

MAX GROSS.
